TOBACCO PIPE

Filed June 6, 1932

FIG. 1.

FIG. 2.

David P. Lavietes

INVENTOR

BY *John H. Lavietes*
his ATTORNEY

UNITED STATES PATENT OFFICE

DAVID P. LAVIETES, OF BROOKLYN, NEW YORK

TOBACCO PIPE

Application filed June 6, 1932. Serial No. 615,519.

My invention relates to improvements in tobacco pipes and is particularly directed to what is termed in the art a "unit", one of the functions of which is to provide a separable connection between the bowl stem and the pipe bit.

An object of my invention is to provide a unit of such construction that while the pipe bit and bowl stem may be readily attached to and detached from each other, nevertheless when the attachment of these parts has been made it cannot be released by a direct pull but only by a torsional or twisting action followed by a pull. I accomplish this object by providing complementary tapered members, preferably both of metal, carried by the bowl stem and bit, respectively, and designed to be engaged and disengaged as desired.

Another object of the invention is to assure a perfect connection between the stem and bit irrespective of any wear to which the tapered members may be subjected, and I accomplish this object by providing a certain tolerance between the stem and bit in order that as wear between the tapered members occurs, their relative positions may be altered without reduction of the tight engagement therebetween.

A further object of the invention is to prevent or to reduce to a minimum the deposit and/or accumulation of moisture in any part of the bowl or bowl stem and to greatly facilitate the removal of such moisture. I accomplish this object by providing in the bit, as distinguished from the bowl stem, a well or chamber which serves as a moisture drain and from which the moisture and products of combustion may be easily discharged.

Other objects and advantages of the invention will appear from the following detail description thereof taken in connection with the accompanying drawing illustrating one form which my improved pipe may take. In such drawing, Fig. 1 is a longitudinal sectional view of a tobacco pipe embodying my invention, and Fig. 2 is a similar view of a fragment of a bit separate from the bowl and having the unit in position at the inner end of the bit.

Referring to the drawing by reference

characters, 10 denotes the bowl, 11 its stem, 12 a short passage providing communication between the bowl and stem, and 13 the pipe bit. These parts may be of any usual approved form and material, although by preference the bowl and stem are of wood and the bit of hard rubber.

The unit, which as its name implies is preferably in one piece, comprises an externally tapered, intermediate plug member 14, a forwardly extending tubular portion 15, a rearwardly extending tubular, externally threaded nipple 16 and an annular flange 17 located between the inner terminus of the thread and the plug 14. When the unit is in position in the stem, the nipple 16 is received in a correspondingly threaded bore 18 in the stem, the rear end of the nipple abutting a shoulder 19 constituted by the wall of an orifice or enlargement 20 of the passage 12, and the flange 17 firmly engaging the forward face of the stem 11. A smoke passage 22 permits of smoke being drawn from the bowl 10 through the open end 21 of tube 15.

If desired, the unit may be cemented into the bowl stem, but for all practical purposes the engagement between the threads of the nipple 16 and those of the bore 18 will provide a sufficiently firm connection to render the use of cement superfluous.

The bit 13 has the usual smoke passage 23 preferably provided at its inner end with an inset metal tube 24 which projects some distance into an enlarged well or expansion chamber 25 at the rear portion of the bit. The main purpose of the tube 24 is to prevent the passage of solid matter into the bit passage 23.

At its rear end, the wall of the well 25 is provided with a countersunk opening 26 into which is set and preferably cemented a thimble or ferrule 27 having a tapered bore complementary to and designed to cooperate with the tapered plug 14. The taper of the plug 14 and of the thimble 27 is desirably of the same magnitude, initially, although this condition may become changed with the wear of the surfaces.

As intimated above, I provide tolerance between the bit and stem, or more accurately

speaking between the complementary tapered surfaces, to assure a tight interengagement of these surfaces despite any wear thereof. One form of such tolerance is shown in the drawing, from which it will appear that the plug 14 and thimble 27 are of unequal length, the thimble preferably being the longer, and a groove 28 is formed between the flange 17 and the end or part of the plug 14 having the greatest diameter. Were the larger end of the plug 14 to contact the flange 17 an invariable stop would be provided for the movement of the thimble 27 and no compensation would be allowed for variation of the extent of such movement, in case of wear between the two tapered surfaces. By providing the tolerance 28, however, if and when the parts wear, the thimble 27 is free to ride up on the plug 14 in proportion to the extent of wear and a tight fit between the tapered surfaces is always assured.

Wear, if perceptible at all, between the surfaces of the plug 14 and thimble 27 is but slight at the most and, therefore, the groove 28 may be and in practice is very narrow so that the space 29 which is left between the inner end of the bit and the outer end of the stem, when the pipe is assembled, is so small as to be barely noticeable.

The bowl portion and bit portion being constructed, respectively, as shown in Fig. 1 of the drawing and it being assumed that the parts are interengaged as there shown, if the bit is to be withdrawn for cleaning of the pipe or for any other purpose, the bowl and bit are relatively twisted or turned whereby the engagement between the tapered surfaces is eased and the bit may be withdrawn by a slight pull. It is found in practice that, due to the provision of the tolerance 28, the engagement of the tapered surfaces is so tight that separation thereof by a straight pull alone is impossible and that initial easing of the interengagement by a twisting motion is indispensable.

An important feature of my invention is the construction which eliminates the deposit of virtually all moisture in the bowl or bowl stem, and compels the deposit, if any, to take place in the well 25 in the stem. The two outstanding advantages of this construction are (1) the absence of moisture in the bowl prevents clogging and fouling thereof and avoids consequent discomfort to the smoker, and (2) a great facility in cleaning the pipe is afforded in that any moisture which has accumulated in the well 25 may be quickly shaken therefrom when the bit is withdrawn from the stem and the exposed parts of the unit may be easily wiped dry and clean. An added advantage of forming the well in the bit rather than in the bowl stem, is that moisture in the well will act somewhat in the nature of a lubricant for the tapered surfaces 14 and 27 and prevent their "freezing".

As is well known in this art, the well acts as an expansion chamber permitting the smoke drawn from the bowl to expand, cool and precipitate the bulk of its contained solids and liquids, so that relatively cool and pure smoke reaches the mouth of the smoker.

Owing to the fact that the joint between the bit and stem is constituted by a metal to metal contact the likelihood of injury or damage to the parts is reduced to a minimum, but should such injury or damage occur, repair or replacement may be effected easily and economically because except for the thimble 27 the entire joint is a single, simply constructed unit.

I claim:

1. In a tobacco pipe comprising a bowl, bowl stem and bit, a joint between the stem and bit comprising complementary, tapered members with tolerance therebetween.

2. In a tobacco pipe comprising a bowl, bowl stem and bit, a joint between the stem and bit comprising a tapered male member projecting from the stem and a tapered female member in the bit, there being tolerance between said tapered members rendering them self-adjusting.

3. In a tobacco pipe comprising a bowl, bowl stem and bit, the combination with a unit in the stem having an externally tapered plug and a flange spaced from the end of the plug having the greater diameter, of a thimble with a tapered bore in the bit designed to self-adjustingly engage the said plug.

4. In a tobacco pipe comprising a bowl, bowl stem and bit, a joint unit carried by the stem comprising an intermediate externally tapered plug, a rearward nipple engaging the stem, a flange at one end of the nipple spaced from the end of the plug having the greater diameter and a forward tubular extension, and a thimble with a tapered bore mounted in the bit and adapted to cooperate with the plug to form a releasable connection between the bit and stem.

5. In a tobacco pipe, the combination with the elements claimed in claim 4, of a thread on the nipple engaging corresponding threads in a bore in the stem.

6. In a tobacco pipe, the combination with the elements claimed in claim 4, of a closure at the forward end of said tubular extension, the latter having a hole in its side wall.

7. In a tobacco pipe, the combination with a bowl stem carrying a joint unit including an externally tapered plug, of a bit containing an expansion chamber and a thimble with a tapered bore carried at the inner end of the bit and surrounding said plug, there being tolerance between said tapered plug and thimble.

8. In a tobacco pipe, the combination with the elements claimed in claim 7, of a tube extending into one end of a smoke passage in

said bit and extending into said expansion chamber.

9. In a tobacco pipe comprising a bowl, bowl stem and bit, a joint between the stem and bit comprising a unit including an externally tapered plug and an annular flange adjacent the same, there being a groove between said annular flange and an end of the plug, and a thimble with a tapered bore in 10 said bit adapted to engage said externally tapered plug.

10. In a tobacco pipe, the combination of a bowl, a stem having a threaded bore, a bit having a smoke passage terminating in an 15 expansion chamber of greater diameter than the said smoke passage, a joint union comprising a threaded nipple engaging said threaded bore, a flange at the outer end of said nipple and designed to seat against the outer end of 20 the stem, an externally tapered plug spaced from said collar by a groove, a tubular extension projecting forwardly from said plug, and a thimble with a tapered bore countersunk in said bit and adapted to engage said 25 plug, the said plug and tubular extension being located in the expansion chamber where the bit and stem are connected to each other.

In testimony whereof I have affixed my signature.

DAVID P. LAVIETES.
